UNITED STATES PATENT OFFICE

139,298

DESIGN FOR A BABY'S MATTRESS COVER

Sam Trossman, Chicago, Ill., assignor to Sam Trossman, Norman Trossman, Harold Trossman, and Marvin Trossman, doing business as Esteem Bedding Company, Chicago, Ill.

Application August 1, 1944, Serial No. 114,679

Term of patent 14 years

(Cl. D92—2)

To all whom it may concern:

Be it known that I, Sam Trossman, a citizen of United States and a resident of the city of Chicago, in the county of Cook and State of Illinois, have invented a new, original, and ornamental Design for a Baby's Mattress Cover, of which the following is a specification, reference being had to the accompanying drawing, forming a part thereof.

The figure is a plan view of a baby's mattress cover, showing my design.

I claim:

The ornamental design for a baby's mattress cover, substantially as shown.

SAM TROSSMAN.
